(57) **CLAIM**

The ornamental design for a walking staff with tripod base, as shown and described herein.

DESCRIPTION

FIG. 1 is a top perspective view of a walking staff with tripod base, with the tripod in the extended position, in accordance with the present invention;

FIG. 2 is a bottom perspective view of the walking staff of FIG. 1 in accordance with the present invention;

FIG. 3 is a cross-sectional view taken along line 3—3 of FIG. 2;

FIG. 4 is a top front perspective view of the walking staff of FIG. 1, with the tripod in the retracted position, in accordance with the present invention;

FIG. 5 is a cross-sectional view taken along line 5—5 of FIG. 4;

FIG. 6 is a back side elevation view of the walking staff of FIG. 4;

FIG. 7 is a right side elevation view of the walking staff of FIG. 4;

FIG. 8 is a left side elevation view of the walking staff of FIG. 4.

FIG. 9 is a side elevation view of the walking staff of FIG. 1 with the shaft in the extended position and the tripod in the retracted position; and,

FIG. 10 is a side elevation view of the walking staff of FIG. 1 with the shaft in the extended position and the tripod in the extended position.

The broken line showing environment is for illustrative purposes only and forms no part of the claimed design.
